A CORPORATION OF PENNSYLVANIA.

METHOD OF AND APPARATUS FOR MARKING METAL ARTICLES.

Application filed December 11, 1923. Serial No. 679,967.

To all whom it may concern:

Be it known that we, HAROLD R. WADE and HARLEY M. FRINK, residing at Pittsburgh, in the county of Allegheny and State 5 of Pennsylvania, both citizens of the United States, have invented or discovered certain new and useful Improvements in Methods of and Apparatus for Marking Metal Articles, of which improvements the following 10 is a specification.

Our invention relates to the marking of metallic articles and is found both in method and in the apparatus by which the method is performed. It is particularly applicable to 15 articles which are superficially plated, and has by us been specifically applied to the marking of tin cans when filled with a marketable commodity and closed. In that 20 particular application we shall show and describe it.

Many articles are prepared for the market by canning. Our invention even in this special field is not in any way limited, but is applicable generally to the marking 25 of the can which contains canned goods, whether those goods be liquid or dry, whether they be food substances or other articles of merchandise,—paint, for example, or photographic films,—whether the can be 30 hermetically tight, as is ordinarily the case with food products, or merely adequately closed, as is the case with baking powder, for example.

It is often desirable to place upon a can, 35 after it has been filled and closed, some mark, words, or legible sign, to afford particular advice about the contents,—for example, the date of packing. And it is common practice to print such marks upon the 40 surface of a can, using a rubber stamp and ink. Marking so applied is not wholly and under all circumstances satisfactory. It is liable to mutilation, and in consequence of handling or in consequence of other conditions to which the can may be exposed,—moisture, for example, or heat—the marks 45 may be destroyed or may become so far obscured as to be illegible and valueless.

In other branches of the arts it is common 50 to place intelligible marks upon the surfaces of articles by sinking the marks into the surface under a powerfully driven die. But this method of marking is not ordinarily

applicable to the marking of cans because ordinarily the filled can is not sufficiently 55 rigid to withstand the blow and to receive without mis-shaping or injury a clearly defined impression of the die, an impression such as to be legible.

Our invention achieves without any distortion or injury to the can a marking which 60 is at once clearly legible and is under all ordinary conditions ineradicable. It consists in effecting localized fusion of the metal surface along lines and over areas which 65 constitute the intended intelligible marks. In consequence of fusion the resolidified metal is changed in appearance from the unfused metal of adjacent parts of the surface of the article. Perhaps there is slight displacement 70 of the fused metal. But the consequence and effect are that the article is branded and bears ineradicably the intended mark.

We preferably achieve the result indicated by providing a die formed of a material whose fusion point is relatively high and which is capable of being shaped and pressed to form a tool with the desired mark or letter formed on it by surface-shaping, 75 preferably in sharp-edged relief. The die will be made of metal, ordinarily of steel. This steel die—for the effect is similar to that of a die—is heated and it is brought, 80 along the edges of the character formed in 85 relief upon it, into contact with the surface of the article to be marked. The temperature is sufficient to effect fusion of the metal under the die along the lines and over the surfaces of contact. The article is not otherwise heated, and its surface will otherwise 90 remain unchanged. When the die has been applied and has had the effect indicated, and has been removed again, the fused metal within the small areas heated will solidify 95 again, and the desired marking will remain, legible because of the changed condition, or perhaps because of the displacement, of the metal affected, and the marking will be ineradicable. In dealing with such material as 100 tin-plated steel, such displacement of the tin as may occur will not expose the underlying steel. In the accompanying drawings a machine is illustrated in which and in the operation of which our invention is 105 embodied and achieved. Fig. I is a view of

the machine in front elevation, Fig. II a view in side elevation, and Fig. III a view in plan from above.

The machine is adapted for use in a canning establishment and is here shown in coordination with an endless-belt conveyor, of a sort commonly in use for conveying cans one by one as they come filled and sealed from one station of preparation or of treatment to another or to a place of delivery.

Such an endless-belt conveyor is found in the sprocket chain A equipped with a block B (ordinarily there are many of these standing at intervals along the length of the chain) adapted to engage and push a can C along a runway D.

At a suitable point along the runway and immediately adjacent the runway is set a vertically standing and immovable post 1, 20 and adjacent the post a vertically standing shaft 2 is mounted for rotation. Means of rotating the post synchronously with the travel of cans along the runway are found in a sprocket wheel 3 which, engaged by 25 and rotated by the sprocket chain A, drives, through the bevel-gears shown, the shaft 2.

In the post 1 is formed a vertical slideway, in which a head 4 is movable, and a screw 5 is provided and a hand-wheel 6, 30 by which the position of the head 4 in the slideway may be adjusted with accuracy. The adjustable head 4 encircles also shaft 2 and slides upon it.

Borne in head 4 is a horizontally extending rotatable shaft 7, and means are 35 provided by which shaft 2 under rotation imparts rotation to shaft 7. Such means are found in a bevel gear 8 which borne rotatably in head 4 is splined to shaft 2 and 40 moves integrally with head 4 as head 4 slides along shaft 2, and in a companion bevel gear 9 borne by shaft 7.

Shaft 7 carries a freely swinging, radially extending fork 10, and between the 45 prongs of the fork is rotatably carried a shaft 11. Shaft 11 carries integrally an essentially cylindrical die-holder 12, and in the face of the die holder is a seat 13 in which an assembly of dies may be 50 removably introduced and secured. The dies are formed of tool steel and are substantially such as are used to impress into or raise upon the surface of a plate of metal identifying marks and characters; that is to say, the marks or characters are formed in 55 relief with sharp chisel-like edges. A carrier 14 may be provided, adapted to be seated in holder 12, and in which an assembly of individual dies may be made, to afford a legend which shall give the particular advice desired. In the assembly the dies stand in relief from a cylindrical surface.

The holder is provided internally with 60 electrical heating apparatus, as is indicated by the binding posts 15 and the lead wires

16. The lead wires are, as is ordinarily the case, flexible, to allow free turning of the die-holder 12 in its bearings in fork 10. The heating apparatus is such in character and the current supplied is of such power 70 as to heat the dies when in place in holder 12 to a degree exceeding the fusion point of the metal immediately to be engaged.

The shaft 7 carries an interrupted spur-wheel 17 and shaft 11 carries an interrupted pinion 18. These two members are mounted to make interengagement throughout the extent of their toothed peripheries, as will be perceived on comparing Figs. I and II.

Fork 10 is mounted, as has been said, for free rotation upon shaft 7. From the hub of rotation with which this fork is provided, extend radially and angularly spaced one from another, two fingers 19 and 20. From slide 4 extends in a direction parallel to shaft 11 a rod 21. A contractible spring 22 is provided anchored at opposite ends to finger 20 and to rod 21. Inspection of Fig. II will make plain the condition, that spring 22 tends always to turn the fork 90 clockwise, holding the fork yieldingly in the position shown, with finger 19 bearing upon rod 21. Rod 21 then is a stop, limiting the range of turning of fork 10 in clockwise direction, while spring 22 is a 95 yielding means holding the fork to position with finger 19 abutting upon rod 21, but allowing recession through a sufficient interval and under a superior force in anti-clockwise turning.

The holder 12 is in its bearing in fork 10 provided with a spring return and a stop, so that it may be rotated in its bearing in anti-clockwise direction, as seen in Fig. II, but when after rotation it is released it returns under spring tension to the position shown in Fig. II.

The holder 12, essentially cylindrical, as has been said, is cut away on opposite sides, as indicated at 23. The toothed portion of 110 pinion 18 extends through approximately 180°; the toothed portion of spur-wheel 17 is of substantially the same linear extent as the toothed portion of pinion 18: there is the same number of teeth. Additionally 115 spur-wheel 17 on the untoothed part of its periphery presents a blank surface 26 co-radial with the tips of its teeth and a blank surface 27, co-radial with the bases of its teeth. The numeral 26 indicates a block 120 removably applied to the periphery of wheel 17. This block is made removable and replaceable, to the end that blocks of different length may be applied, adapting the machine to operation upon cans of different 125 size. For it will be understood that the greater the extent of the block 26 peripherally upon wheel 17, the longer will be the interval during which holder 12 remains at rest with one of its flat faces 23 down-

ward, and the further the travel of chain A and of the can borne thereby, before holder 12 rotates under spring tension back to initial position.

- 5 In assembly the parts are correlated as Fig. II indicates: Holder 12 stands normally with its flat faces 23 extending horizontally above and below. It is as has been said yieldingly held against anti-clockwise turning by a spring which presses it clockwise against an abutment. In this position of the holder 12 the pinion 18 which is mounted integrally with it upon shaft 11 stands with the forward end of its toothed segment adjacent spur-wheel 17, in position to be engaged as wheel 17 turns, by the teeth with which wheel 17 is equipped. In normal operation shaft 7 driven from chain A turns clockwise and turns constantly. As it turns spur-wheel 17 intermittently meshes with pinion 18, and intermittently rotates it through a half rotation (anti-clockwise). As the teeth of spur-wheel 17 pass from engagement with the teeth of pinion 18, the elevated blank portion of wheel 17 then engages the rearmost of the teeth upon pinion 18, and holds the pinion for an interval stationary, while spur-wheel 17 continues to turn. Then as this elevated portion passes, pinion 18 is free, and it turns back again (clockwise) under spring tension to its initial position.

The chain A is provided at regular successive intervals with the can-driving blocks B. Coordination is such that spur-wheel 17 makes one rotation while chain A advances through the interval between two successive blocks B, and rotation of die holder 12 is so timed that the dies borne in carrier 14 and seated in seat 13 will engage the surface of can C advancing along ways D on a line vertically beneath the axis of shaft 11. It will of course be understood that the spur-wheel 17 and the pinion 18 are so proportioned that the dies when under rotation will travel at equal speed with the can driven by chain A.

Operation is as follows. The slide 4 is by hand-wheel 6 adjusted vertically in standard 1, according to the height of the cans to be marked. The cylindrical surface within which the dies turn must be with substantial and sufficient accuracy, tangent to the plane in which the can heads advance beneath. Such adjustment having been made, and careful adjustment having also been made between the particular position of pusher blocks B and the circumferential position of the teeth upon spur-wheel 17, cans ready for marking are supplied and carried one by one, by blocks B along ways D. The rim around the head of a can stands ordinarily somewhat higher than the medial surface within the rim. As the can advances to and beyond the position illustrated in Fig. II, the teeth upon spur-wheel

17 presently engage the teeth upon pinion 18 and in consequence die-holder 12 begins its anti-clockwise turning. The advance rim of the can passes beneath holder 12 while still the cut-away portion at 23 affords clearance. Presently thereafter the dies borne by the holder come to tangency upon the surface of the head of the can and advance synchronously with the can through the region of substantial tangency. The dies at 75 the time of contact are highly heated and they effect localized fusion of the surface metal at the very points of contact. After contact the softened metal freezes or solidifies, but carries ineradicably the trace of 80 what has happened. The can is branded with the characters which the dies have so imposed upon it.

The holder 12 continues its power-driven anti-clockwise rotation until after the dies have passed completely beyond the line of tangency directly beneath the axis of shaft 11, and until the cut away surface 23 which was initially uppermost becomes lowermost. In this position the holder continues (in 90 consequence of the engagement of the raised blank area 26 upon spur-wheel 17 with the rearmost tooth of the series upon pinion 18) until the can has passed beyond the range of the turning holder 12. Then the holder, 95 free of other restraint, revolves under the tension of its return spring to its initial position, where it is ready for repetition of the operation upon the next advancing can.

It will be perceived that while the invention involves essentially the localized and superficial fusion of the surface of metal, displacement of the fused metal by the die is not forbidden. Indeed it may be well so to adjust the apparatus (and practically it 105 is quite impossible to prevent this effect) that the edges of the dies shall actually sink below the surface, where by high temperature they have effected softening of the metal. The consequent displacement of the 110 softened metal tends to heighten the effect.

We have said the metal is in the practice of our invention fused locally, and such is essentially true. But it will be borne in mind that fusion is a change of state which 115 in the case of metals generally is approached by a gradual softening. And when we say fusion we mean such a change of state effected by heat in the manner described as shall, either with or without physical displacement of the metal under the die, leave 120 permanently upon the metal the trace of the change which has been effected.

Returning to the operation it remains to remark that the fork 10 affords spring-backed support for die-holder 12 and allows the die-holder to yield upwardly while the marking operation is in progress. Cans are not so exactly uniform in dimensions and ordinary machinery is not so perfect in its 130

precision as to afford actual tangency of the die upon the can always, in every case, precisely the same. In practice, therefore, slide 4 is so positioned as to insure contact of die 5 upon can, even upon the smallest can in a run. Upon substantially all the cans, therefore, the die will bear with some pressure derived from spring 22, and therefore there will practically always be some 10 placement of the metal when softened under the die.

The invention finds primary and immediate application in the making of tin cans, and the material acted upon in this 15 case is essentially a sheet of metal which under the conditions of operation is infusible, covered with a skin of metal which under the conditions is fusible. Manifestly the invention is not limited in this particular, but may be applied to any object, whether homogeneous or compound in character, whose substance may be superficially softened when subjected to the operation described so as to leave the desired trace imposed by heat, with or without concomitant pressure, upon it.

In Fig. II we have shown a second seat 24 formed in die-holder 12 and adapted to contain a second die-carrier 25. It will be 30 understood that the dies of a carrier inserted at this point will be ineffective in the operation as described. But it will be realized that a carrier so borne by the holder, and the dies which it carries too, will be heated. 35 In these marking operations it often is advantageous to prepare two die assemblies for successive use and to have a second hot and substantially ready to take the place of the first and to serve immediately, without waiting for it to become gradually hot. When a 40 second assembly so succeeds a first, a third may be slipped to seat 24, that it in turn may become heated, ready when required to take the place of number two.

45 Our invention in method is, as we have said, found in the operation of the machine we now have described.

We claim as our invention:

1. The method herein described of imposing upon a surface of fusible material an 50 intelligible mark which consists in maintaining the surface elsewhere in solid and unfused state and while so maintaining it, effecting localized fusion followed by resolidification over a restricted area within 55 such surface.

2. The method herein described of imposing upon a surface of fusible material an intelligible mark which consists in applying to 60 the surface while maintained elsewhere in solid condition a die heated beyond the point of liquefaction of such material, whereby localized fusion is effected over the areas of die application, and then allowing the 65 fused metal to solidify.

3. The method herein described of imposing upon a surface of fusible material an intelligible mark which consists in maintaining the surface elsewhere in solid and unfused state and while so maintaining it, fusing and displacing the material locally, over restricted areas within such surface, beneath a heated die, and then allowing the fused material to solidify again. 70

4. The method herein described of marking a can of goods which consists in effecting over a restricted area within such a surface otherwise solid, a localized fusion, followed by resolidification. 75

5. In a machine for marking articles and in combination with a conveyor adapted to carry the articles singly along a predetermined course a die carrier mounted for oscillation upon an axis in a cylindrical path, a die borne by said carrier and in the course of oscillation traveling tangent to the course of advance of the article on said conveyor, such die so borne being yieldingly held to such cylindrical path, and means engaging the die carrier and by such engagement causing the die to advance in its path at equal speed with the advance of an article on said conveyor, and throughout the range of contact between die and article. 80

6. In a machine for marking articles the 90 combination with conveyor means adapted to advance articles one by one along a predetermined path, a heat giving rotatable cylindrical die holder provided with a plurality of seats for die carriers, and heating 100 means borne by said die-holder in operative relation to both of said die seats. 95

7. In a machine for marking filled cans, the combination with means for causing cans to advance singly and at regular intervals along a predetermined path, a cylindrical die-holder with a flat side arranged adjacent such path of can advance and standing normally with its flat side toward such path, a die borne by said die-holder, rotating means engaging said die-holder and rotating said die-holder and the die borne thereby throughout the range of contact between the die borne by the holder and a can advancing along said path. 110 105

8. In a can marking machine and in combination with the driving element A of a conveyor apparatus, the block 4 adjustable with respect to the said driving element and carrying the rotatable shaft 7 with its spur-wheel 17, means for rotating shaft 7 in response to advance of driving element A, the fork 10, shaft 11 with its pinion 18 and die-holder 12, borne by said block, and means for yieldingly maintaining fork 10 in predetermined angular position upon shaft 7. 120 115

9. In a machine for marking filled cans, the combination with means for causing a can to advance along a predetermined path, a cylindrical die-holder with opposite flat 130 125

sides arranged adjacent such path, means for causing the die-holder initially stationary to rotate through a half rotation at a surface speed equal to the speed of can advance, then to remain stationary, and finally to rotate in opposite direction to its initial stationary position.

In testimony whereof we have hereunto set our hands.

HAROLD R. WADE.
HARLEY M. FRINK.
